CLAIM

The ornamental design for a lounge chair, as shown and described.

DESCRIPTION

FIG. 1 is a front perspective view of a lounge chair according to a first embodiment;

FIG. 2 is a rear perspective view thereof;

FIG. 3 is a front view thereof;

FIG. 4 is a first side view thereof;

FIG. 5 is a second side view thereof;

FIG. 6 is a rear view thereof;

FIG. 7 is a top view thereof.

FIG. 8 is a front perspective view of a lounge chair according to a second embodiment;

FIG. 9 is a rear perspective view thereof;

FIG. 10 is a front view thereof;

FIG. 11 is a first side view thereof;

FIG. 12 is a second side view thereof;

FIG. 13 is a rear view thereof; and,

FIG. 14 is a top view thereof.

The evenly dashed broken lines depict portions of the lounge chair that form no part of the claimed design.

The long dash-short dash broken lines depict the boundaries of the claim and the lines themselves form no part of the claimed design.
